UNITED STATES PATENT OFFICE.

HENRI G. CHATAIN, OF ERIE, PENNSYLVANIA, ASSIGNOR TO GENERAL ELECTRIC COMPANY, A CORPORATION OF NEW YORK.

LOCOMOTIVE.

1,076,407.

Specification of Letters Patent.

Patented Oct. 21, 1913.

Application filed May 13, 1912. Serial No. 696,828.

To all whom it may concern:

Be it known that I, HENRI G. CHATAIN, a citizen of the United States, residing at Erie, in the county of Erie, State of Pennsylvania, have invented certain new and useful Improvements in Locomotives, of which the following is a specification.

The present invention relates to locomotives and has for its object to improve and 10 simplify their construction.

Briefly stated, in carrying out my invention an internal combustion engine is provided that is divided into two principal parts and between said parts is situated the 15 field magnet frame of an electric generator which supplies current to motors whose rotors are mounted on the locomotive axles. The magnet frame of the generator may form an integral part of the engine frame or 20 form a uniting member therefor. In either case it has great advantages in the way of simplicity in construction and ease of manufacture and alinement. Projecting downwardly from the base portion of the engine 25 frame are parts of the magnet frames of the motors, said frame parts being parallel and arranged in pairs, each pair embracing an axle and the rotor of the motor. On these frame parts or pieces are mounted pole 30 pieces and energizing coils for the field magnets of the motors. The under side of the engine frame adjacent the rotors of the motors must be of such cross-section that it will carry the magnetic flux due to the field 35 windings. The relation of the field poles and windings to the armature or rotors on the axles is such that the trucks and armatures can be removed from below. The entire weight of the engine, generator, and 40 pole pieces of the motors is carried by the cab or body of the locomotive and said cab or body is supported upon springs carried by the trucks.

I have illustrated my invention in connection with a locomotive having two trucks, and owing to the fact that the engine, generator and magnet frames of the motors form a unitary structure care should be exercised not to make the wheel base too 45 long, since otherwise the locomotive would not readily go around curves in the track.

In the accompanying drawing, which illustrates one of the embodiments of my invention, Figure 1 is a side view, partially in

section, of my improved locomotive, and 55 Fig. 2 is a transverse section thereof.

1 indicates the cab of the locomotive which may be of any suitable shape and construction and is provided with floor sills 2. Located within the cab is a multi-cylinder internal combustion engine that is divided into two principal parts 3 and 4. Between these parts is located an electric generator whose field magnet frame 5 acts as a connecting member to unite the base portions 6 and 7 of the engine. The means for uniting the parts is also shown in Fig. 2 where 8 indicates a flange formed on the engine base, which is secured to the field magnet frame of the generator by bolts 9.

The engine is provided with laterally extended feet 10 that rest on the main sills 2, the latter being formed of I-beams. The base of the engine is divided into upper and lower parts, the plane of division being horizontal and coinciding with the axis of the main shaft 11. The shaft 11 is common to both parts of the engine and also to the armature 12 of the electric generator. The shaft may be made in one piece or in two 80 or more pieces united by couplings.

13 indicates the commutator of the generator, the brushes therefor having been omitted to simplify the illustration.

Two trucks 14 are provided which may be 85 of any suitable construction. Each truck is provided with two leaf springs 15 located on opposite sides. These springs are secured to the sills of the locomotive cab by the hangers 16. The sides of the truck are 90 united by a frame 17. These trucks are not arranged to swivel under the locomotive as it is commonly the case. Mounted on each truck axle are the usual track wheels and the rotor or armature 18 of an electric motor. 95

Depending from the base of the engine frame are projections 19 that are arranged in pairs, each pair being situated on opposite sides of an axle. These projections are integral with the base of the engine and 100 form a part of the magnet frame of the motors. In order to carry the magnetic flux between these projections, the lower wall of the engine base has to be thickened as indicated at 20. Referring to Fig. 2, it will be 105 seen that the projections 19 are relatively long and narrow. Their width is determined by the length of the armature 18.

Each projection 19 is provided with a pole piece 21 having a pole shoe 22 and on each pole piece and shoe is a field winding 23. Each armature is provided with a commutator 24, the brushes and the brush rigging having been omitted to simplify the illustration. All of the motors are similarly constructed and hence further description is unnecessary. The motors are adapted to receive current from the electric generator subject to controlling mechanism of any suitable character.

It will be observed that the diameter of each motor armature is slightly less than the distance between the field coils. This permits the engine and motor field magnets to move up and down with respect to the armature 18 and the axles under the action of springs 15. This same arrangement permits of removing the trucks by raising the engine and cab, or, what is the equivalent, holding the engine and cab in fixed position and lowering the trucks.

My improved arrangement has the great advantage of simplicity and strength. The lower half of the engine base or frame with its projections is a simple casting to make and machine. The surfaces that require machine work are perpendicular to each other, which makes for ease of manufacture, and such machine operations as are necessary are of a very simple character. By uniting the parts of the engine base through the field magnet 5 of the generator an exceedingly rigid structure is obtained and one that is not liable to get out of line or be sprung. By providing each part of the engine base with laterally projecting feet 10 which rest on the main sills 2, the weight of the engine is well distributed and it can be securely fastened in place. As shown, the generator is entirely supported by the adjacent ends of the engine frame, although it may be provided with feet on opposite sides 45 to rest on the sills if desired.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new, and desire to secure by Letters Patent of the United States, is:—

1. In a locomotive, the combination of an engine, projections that extend downwardly from the engine base and form with the base the magnet frame of an electric motor, field coils carried by the projections, a truck, an armature for the motor that is mounted on an axle of the truck and is located between said projections, and a generator driven by the engine which is adapted to supply current to the motor.

2. In a locomotive, the combination of an engine, projections which are formed integral with the engine base and are arranged in pairs to form the magnet frames of electric motors, field coils carried by the projections, a truck, armatures for the motors which are mounted on the truck axles, and an electric generator driven by the engine which is adapted to supply current to the motors.

3. In a locomotive, the combination of a cab, a truck therefor, springs interposed between the truck and cab, an engine supported by the cab and provided with integral and downwardly extending parallel projections forming magnet frames for motors, windings carried by the projections, rotors for the motors that are mounted on the truck axles and are situated between the projections, and an electric generator driven by the engine which is adapted to supply current to the motors.

4. In a locomotive, the combination of an engine that is made in two principal parts, an electric generator driven by the engine whose magnet frame unites said parts, integral and downwardly extending projections formed on the under side of each part of the engine and arranged in pairs to form magnet frames for the motors, windings mounted on the projections, a pair of trucks one under each part of the engine, and rotors for the motors mounted on the truck axles which are situated between said projections and are adapted to receive current from the generator.

5. In a locomotive having floor sills, the combination of a prime mover supported by the sills and having integral projections that form a magnet frame, energizing coils that are carried by the projections, a motor armature situated between the projections and coils and carried by an axle, an electric generator driven by the prime mover whose magnet frame forms a unitary part of the frame of the prime mover and is adapted to supply current to the motors.

6. In a locomotive, the combination of a cab having longitudinal sills, an engine located within the cab which is divided into two principal parts, feet on said parts that rest on the sills for supporting the engine, and an electric generator situated between the parts of the engine whose magnet frame unites the parts of the engine into a unitary structure.

7. In a locomotive, the combination of an engine having a base which is divided horizontally into an upper and a lower part, feet secured to the lower part of the base for supporting the engine, and projections formed integral with the under side of the lower part of the base and arranged in pairs which form magnet frames for electric motors, the portion of the engine base between

each pair of projections being thickened to provide the necessary cross-section to carry the magnetic flux.

8. In a locomotive, the combination of a cab having floor sills, trucks for the cab, springs interposed between the trucks and cab, a prime mover supported by the floor sills and having downwardly extending projections that form magnet frames, energizing coils carried by the projections, motor armatures mounted on axles of the trucks and situated between the projections and

coils, said armatures and coils being capable of relative vertical movements, an electric generator driven by the prime mover whose 15 magnet frame forms a unitary part of the frame of the prime mover and is adapted to supply current to the motors.

In witness whereof, I have hereunto set my hand this 11th day of May, 1912.

HENRI G. CHATAIN.
